CLOTHESLINE REEL

Ethan Egbert Black, Wichita, Kans.

Application June 19, 1935, Serial No. 27,445

3 Claims. (Cl. 242—101)

The device forming the subject matter of this application is a windlass for handling a clothes line. The invention aims to supply a device of the class described, so constructed that a twisted 5 wire clothes line of unusual length may be handled. Another object of the invention is to mount the device in such a way that it can swing laterally and keep the reel in vertical alignment with the clothes line. A further object of the invention 10 is to improve the tightener and the back stop pawl. The invention aims to supply a device of the class described in which the working parts, as well as the reeled-in clothes line, will be housed and protected from dirt and from the 15 effects of the weather.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it 25 being understood that changes in the precise embodiment of the invention herein disclosed, may be made within the scope of what is claimed, without departing from the spirit of the invention.

In the accompanying drawings:

Fig. 1 shows, in side elevation, a device constructed in accordance with the invention; Fig. 2 is a section on the line 2—2 of Fig. 1; Fig. 3 is a section on the line 3—3 of Fig. 2; Fig. 4 is a section on the line 4—4 of Fig. 1; Fig. 5 is a section on the line 5—5 of Fig. 4; Fig. 6 is a section on the line 6—6 of Fig. 1.

The device forming the subject matter of this application preferably is made of non-rusting 40 metal throughout. It comprises a support S, including a bracket plate 1 having openings 2 by means of which the bracket plate can be attached to any accessible or convenient object. The bracket plate 1 has outwardly extended ears 3.

The letter C marks a circular casing, including a tubular hub 4, having an internal circumferential recess 5. A fixed annular side plate 6 is formed integrally with one end of the hub 4 and carries an outwardly convexed rim 7, which 45 overhangs the hub 4. The casing C has a laterally projecting block 8, received between the ears 3 of the bracket plate 1. Pivot elements 9 are journaled in the ears 3 of the bracket plate 1 and are threaded into the block 8 of the casing C, the construction being such that the casing C

can swing laterally or horizontally, thereby keeping the reel (hereinafter described) in line with the clothes line that is being paid off or wrapped about the reel.

It can be seen in Figs. 2 and 3 that roller bearings 10 extend across the recess 5 of the hub 4 and roll at their ends on the perimeter of the hub, loose spacers 11 being interposed between the roller bearings. An annular side plate 12 is attached to one end of the hub 4 by securing elements 14 threaded into studs 15 on the hub. The roller bearings 10 and the spacers 11 are prevented from moving crosswise of the casing C to any great extent, because they are interposed between the side plate 6 and the side plate 12. 10 The side plate 12 does not extend out to the overhanging rim 7 of the casing C, and, consequently, there is an annular space 16 at one side of the casing, between the removable side plate 12 and the rim 7. 20

The letter R designates a reel, including an annular base 17 which turns on the roller bearings 10, as Fig. 3 will show, an easy rotation of the reel thus being secured. In cross section, the reel R is trough-shaped, as Fig. 2 will show. The reel comprises a wall 18, disposed adjacent to the side plate 6 of the casing C, and a wall 20 disposed inside of the annular plate 12 of the casing. The reel, thus, is housed within the casing. The wall 18 of the reel R has radial openings or slots 19, shown best in Fig. 3. The wall 20 of the reel R carries an outwardly extended screw pin 21, on which a handle 22 can turn, the handle projecting outwardly through the annular opening 16 in the casing C. 30

The side plate 6 of the casing C carries a socket 23 into which is threaded a tubular bushing 24. A back stop pawl 25 is mounted for longitudinal sliding movement in the bushing 24 and is advanced by a compression spring 26, located within the bushing 24. The back stop pawl 25 has a laterally projecting pin 27 received in a slot 28 in the outer end of the bushing 24 and keeping the pawl from rotating on its axis. At its outer end, the pawl 25 has a manipulating head 29. The inner end of the back stop pawl 25 is beveled as shown at 30 in Fig. 5, and the parts of the wall 18 of the reel R that lie between the seats 19 are rounded a little, as shown at 31, to cooperate with the beveled surface 30 of the back stop pawl 25, the construction being such that the back stop pawl 25 will click whilst the reel R is being rotated by means of the handle 22 to wind up the line; but when the straight side (Fig. 5) of the back stop pawl 25 is in one of the seats 35

19 of the reel, retrograde rotation of the reel will be prevented.

The side plate 6 of the casing C has an outwardly projecting stud 32, on which a tightener, 5 in the form of a lever 33, is mounted to swing, both parallel to the side plate 6 of the casing and at right angles thereto. The lever tightener 33 is provided with a fixed finger 34, extended inwardly through an arcuate slot 35 in the side 10 plate 6 of the casing C, the finger 34 being adapted to be engaged in any of the ratchet openings 19 of the reel. The tightener 33 is held against the side plate 6 of the casing C (Fig. 2) with the finger 34 in one of the openings 19 of the reel, 15 by a compression spring 36, disposed spirally about the stud 32, the outer end of the spring 36 being engaged by a washer 37 held on the end of the stud 32 by a securing element 38. At its inner end, the spring 36 is supplied with an outwardly projecting arm 39 engaged between two 20 projections 40 on the lever tightener 33. The side plate 6 of the casing C has a stop 41 with which the finger 34 of the tightener 33 engages, under circumstances to be pointed out hereinafter. The 25 finger 34 of the tightener 33 has a beveled surface 42, shown in Fig. 6 and to be alluded to herein-after.

The line 43 may be a twisted wire line of much 30 greater length than customary. The line 43 extends into the casing C through an opening 44 in the rim 7 of the casing, the inner end of the line being made fast by any suitable means indicated at 45 in Fig. 2 to the base 17 of the reel R.

In practical operation, let it be supposed that 35 the lever tightener 33 has been swung to the left from the position of Fig. 1, the beveled surface 42 of the finger 34 on the tightener enabling the finger to move readily out of the opening 19 of the reel, and out of the arcuate slot 35 in the casing C, against the thrust of the spring 36, until the 40 finger 34 is in abutment with the stop 41. The tightener 33 now is in inoperative position and will be held in that position by the pressure of the spring 36 of Fig. 2.

45 The operator pulls out the back stop pawl 25, until it is disengaged from the opening 19 of the reel, the back stop pawl being rotated until the pin 27 of the back stop pawl rests against the outer end of the bushing 24. This leaves the reel R free to rotate, and the operator can pay out as much of the line 43 as he wishes.

When the operator desires to tighten the line 50 43, the back stop pawl 25 is restored to the clicking position of Fig. 5, and the reel R first is rotated, by means of the handle 22, to take in so much of the slack in the line 43 as can be handled without great effort, the back stop pawl 25 cooperating with the reel, to prevent retrograde rotation of the reel, the slack thus being held.

60 When the reel R, manipulated by the handle 22, begins to turn with difficulty, the lever tightener 33 is swung back to the position of Figs. 1 and 2, the finger of the tightener 33 cooperating with the openings 19 of the reel. By swinging the tightener 33 back and forth, with the finger 34 in the arcuate slot 35 of the casing C, the reel R may be rotated further, under the increased purchase afforded by the tightener 33, to take more slack out of the line 43 and to render the line 70 taut.

It is to be observed, as shown in Fig. 2, that the reel R is housed in the casing C, within the rim 7. It is impossible, therefore, for the line 43 to uncoil and jump off the reel, when the line is slack. The construction last referred to renders 5 it possible to use a long and somewhat heavy twisted wire line without any inconvenience. The line 43, when wound on the reel R is housed and kept clean.

Practically all of the reel R, also, is housed 10 within the casing C, saving so much of the reel as may be exposed through the annular opening 16, that opening being provided in order that the handle 22 may be employed.

The device is highly satisfactory from a mechanical point of view, and, moreover, it is an article which will detract nothing from the appearance of the structure whereon it is mounted. A glance at Fig. 2 will show that by taking off 15 the side plate 12, the device may be taken down 20 quickly and be assembled without difficulty.

Having thus described the invention, what is claimed is:

1. In a device of the class described, a casing 25 including a tubular hub provided with a fixed side plate having an annular rim disposed about the hub and spaced therefrom, there being an annular opening in one side of the casing, between the rim and the hub, a reel U-shaped in 30 cross section and including an annular base provided with oppositely disposed outstanding side flanges, the base of the reel being of such internal diameter that it can be slipped over the hub, thereby to dispose the reel within the casing 35 and to journal the reel on the hub, a lateral handle on one side flange of the reel and extended outwardly through the annular opening, said side flange extending to the rim of the casing, a ring overlapping said side flange of the reel and overlapping the hub, the ring forming the inner 40 boundary of the annular opening, and means for securing the ring detachably to the hub, the reel being held between the ring and the fixed side plate of the casing, against appreciable trans- 45 verse movement.

2. A device of the class described, constructed as set forth in claim 1, in combination with trans- 50 verse rollers located between the hub and the base of the reel, and spacers interposed between the rollers, the rollers and the spacers being restrained against endwise movement by the ring and by the fixed side plate of the casing.

3. A device of the class described, constructed as set forth in claim 1, and wherein the other 55 side flange of the reel has a ratchet, the side plate of the casing having an arcuate slot, a lever having a fixed pawl extended through the slot and engaged with the ratchet, means for mounting the lever for swinging movement substantially 60 parallel to the side plate, whereby the pawl will impart rotation to the reel, and for mounting the lever for swinging movement at right angles to the side plate, whereby the pawl can be disengaged from the ratchet and withdrawn from the 65 slot and rested against the side plate when the lever is swung in a direction substantially parallel to the side plate, and a holding pawl mounted on the side plate and engageable with the ratchet.
